UNITED STATES PATENT OFFICE.

WILLIAM C. STEWART, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-LEVELING MACHINE.

1,268,295.

Specification of Letters Patent.

Patented June 4, 1918.

Application filed March 23, 1917. Serial No. 156,827.

To all whom it may concern:

Be it known that I, WILLIAM C. STEWART, a subject of Great Britain, residing at Swampscott, in the county of Essex and 5 State of Massachusetts, have invented certain new and useful Improvements in Sole-Leveling Machines; and I do hereby declare the following to be a full, clear, and exact description of the invention, such as 10 will enable others skilled in the art to which it appertains to make and use the same.

The present invention relates to sole leveling machines and more particularly to a heel clamp for holding a shoe in position upon 15 the last of a sole leveling machine of the rolling pressure type.

It is customary in this type of machine to provide means for holding the heel end of the shoe down upon the last during the 20 operation of the pressing form upon the fore-part of the shoe and to remove the clamping means into an inoperative position when the form is in engagement with the heel portion of the shoe sole. The actuating mechanism 25 for the heel clamp is arranged to impart simultaneous inward and downward movements to the clamp to cause the latter to project over and engage with the heel end of the sole. With this mode of operation it 30 sometimes happens, however, that the heel clamp engages with the sole prior to the completion of the inward movement which tends to injure the sole or displace the latter relative to the last.

35 The object of the present invention is to provide a heel clamp of an improved form which is actuated automatically to engage with and clamp the heel end of the sole without tendency to damage the sole or displace 40 the sole relative to the last.

With this object in view a feature of the invention contemplates the provision in a machine of this type of a heel clamp movable toward and from the last and mechanism for actuating the clamp to impart an inward movement to the clamp until the latter engages with the end of the shoe and to thereafter move the clamp longitudinally into operative engagement with the heel 45 portion of the sole.

Still further features of the invention

consist in certain novel features of construction, combinations and arrangements of parts hereinafter described and claimed, the advantages of which will be obvious to those 55 skilled in the art from the following description.

The preferred form of the invention is illustrated in the accompanying drawings, in which Figure 1 is a view in side elevation of a sole leveling machine having the invention embodied therein; Fig. 2 is an enlarged detail view in side elevation of the heel clamp and its actuating mechanism; and Fig. 3 is a top plan view of the heel clamp 60 actuating mechanism.

The machine illustrated in Fig. 1 of the drawings has the same construction and mode of operation as that shown and described in the patent to Holt No. 944,620, 65 December 28, 1909. This machine is a double machine and comprises two sole pressing forms 10 mounted on carriers 12, and two coöperating lasts 14 mounted on jacks or last posts 16. The last posts 16 are adjustably mounted in carriers 18, and are arranged to be longitudinally adjusted in said carriers by means of handles 20 and hand wheels 22. Each form carrier is connected to its coöperating last carrier by means of a 70 link 24, and the last carriers are connected by means of links 26 to cranks on concentric crank shafts 30. Only one set of devices for operating the crank shafts 30 is illustrated. In the illustrated device the crank 75 shaft 30 is driven from the shaft 32 by means of a worm 34 and worm wheel 36 mounted on the shafts 32 and 30, respectively. The shaft 32 is driven by a friction clutch 38, the mechanism for operating which is so arranged that the clutch may be connected by 80 means of a foot treadle, and continue to operate as long as the foot treadle is depressed. Upon releasing the foot treadle, the clutch is automatically disconnected by means 85 of a timing cam on the crank shaft 30 to stop the machine with the last located in a position of presentation for the convenient removal of the shoe.

According to the present invention mechanism is provided for first moving the heel clamp inwardly toward the last until the 90

clamp contacts with the back of the shoe. In this position the sole engaging end of the clamp is positioned above and projects over the heel portion of the sole. The continued 5 operation of the actuating mechanism then causes a downward or longitudinal movement of the clamp in a direction substantially normal to the surface of the sole to cause the clamp to firmly engage with the 10 heel portion of the sole. This mode of operation insures against any movement of the heel clamp along the surface of the sole after the clamp has engaged therewith.

The heel clamp shown in the illustrated 15 embodiment of the invention comprises a plate 40, shaped to project across the heel portion of a sole and adjustably mounted upon the upper end of a rod 42 which is secured to an upstanding arm 44 pivoted 20 upon one arm 45 of a bell crank lever 46. The lever is bifurcated to surround the last post 16, and is pivoted upon a collar 48 journaled upon one arm of a bell crank lever 54 25 pivoted upon the upper end of an arm 56. The arm 56 is supported upon a shaft 58 secured in the frame and forming the fulcrum about which the last carrier 18 rocks. A second arm 55 extends from the arm 56 and is secured at its outer end to the last carrier 18 through a bolt 60. This construction 30 causes the bell crank 54 to partake of the movements of the last carrier 18. The heel clamp is normally moved from the inoperative position shown in full lines in Fig. 2 to an operative position shown in dotted lines in Fig. 2 by a pair of tension springs 40 68 connecting the rod 42 with a stationary arm 78 secured rigidly to the collar 48. The opposite ends of the springs are attached to pins 70 and 72 mounted in the rod and 45 in the arm 78, respectively. When the arm 45 of the bell crank 46 is elevated the heel clamp is retained in an inoperative position through a tail 74 extending from the arm 44 and engaging beneath a set screw 76 50 threaded in the upwardly curved end of the stationary arm 78.

The movements of the heel clamp into and 55 out of operative position are controlled by a stationary cam 62 secured on the shaft 58 and engaged by a cam roll 66 journaled upon the second arm of the bell crank 54, as shown in the drawings. During the initial 60 movement of the pressing form from the heel to the toe of the shoe the bell crank 54 rocks with the last carrier and causes the roll 66 to move over the portion 80 of the cam 62. During the movement of the roll 66 over this portion of the cam the arm 45 of the bell crank 46 and the heel clamp are 65 retained in substantially the positions shown,

in Fig. 2 of the drawings. This will be apparent when it is considered that owing to the engagement of the tail 74 beneath the set screw 76 an inward movement of the heel clamp can only take place when the pivot 84 70 is free to move downwardly.

Coincidently with the separation of the pressing form and the shoe at the heel a sufficient distance to permit the entrance of the heel clamp the roll 66 passes on to the portion 82 of the cam 62. This immediately releases the bell crank levers 46 and 54 and permits the springs 68 to rock the heel clamp inwardly about the pivot 84. This inward movement of the heel clamp takes place in 80 a plane substantially parallel with the plane of the shoe sole as the slight downward movement of the pivot 84 is substantially balanced by the elevation of the heel clamp in moving from the position shown in Fig. 85 2 to a position in engagement with the back of the shoe. This inward movement of the heel clamp continues until the clamp engages with the back of the shoe when thereafter the springs 68 impart a bodily longitudinal movement to the heel clamp in a direction normal to the surface of the sole to bring the clamp into sole engaging position. During the first portion of the inward movement the springs 68 cause the heel clamp to 90 fulcrum about the outer end of the tail 74 until the clamp has engaged with the back of the shoe when thereafter further inward movement is prevented and the heel clamp is moved downwardly into engagement with 95 the shoe sole.

During the operation of the pressing form upon the forepart of the sole the cam roll 66 moves over the portion 88 of the cam 62 and permits the springs 68 to retain the heel 100 clamp in sole engaging position. Upon the return of the pressing form to the heel portion of the sole the cam roll 66 again moves over the portion 80 of the cam 62, rocking the bell crank levers 54 and 46 into substantially the positions shown in Fig. 2 and removing the heel clamp from engagement with the sole. In order to prevent an abrupt return movement of the heel clamp the leaf spring 90 is secured to the rod 42 110 and projects beneath a boss 91 formed upon the bell crank. This spring, as will be clearly evident, restrains the outward movements of the heel clamp away from the shoe when the tail 74 is suddenly brought into engagement with the set screw 76 owing to the elevation of the bell crank 46.

According to the present invention an adjustment of the last post 16 relative to the carrier 18 imparts a corresponding movement to the heel clamp without disturbing the operative relation of the several parts of the heel clamp actuating mechanism. To this end it will be observed that the heel clamp and supporting bell crank lever 46 125 130

are mounted upon the collar 48, secured to the last post, so that the heel clamp partakes of the longitudinal movements of the last post relative to the latter. The bell crank 54 is pivoted independently of the last post, however, and operatively engages with the bell crank 46 through the engagement of the roll 52 with an elongated face 49 formed upon the depending arm of the bell crank 46. With this construction an adjustment of the last post merely moves the roll 52 along the face 49 without disturbing the operative relation of the parts.

The present mechanism is so constructed that it may be conveniently applied to existing machines and with this end in view the arm 56 supporting the bell crank 54 is loosely journaled upon the stationary shaft 58 and is provided with the second arm 55 extending therefrom which is secured at its outer end to the jack carrier 18.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A sole pressing machine, having in combination, a pivotally-mounted last post, a last on said post, a coöperating sole pressing form, means for relatively oscillating the last and form to level the sole of a shoe, a heel clamp supported on said post, and means, controlled by the movement of the last, to swing the clamp into engagement with the end of the shoe on the last while maintaining said clamp beyond the surface of the sole and to longitudinally draw the clamp into contact therewith after the clamp engages the end of the shoe.

2. A sole pressing machine having, in combination, a pivotally-mounted last post, a last on said post, a coöperating sole pressing form, means for relatively oscillating said last and form to level the sole of a shoe, a heel-clamp supported on said post, and spring-operated means, controlled by the movement of the last, to swing the clamp into engagement with the end of the shoe while maintaining said clamp beyond the surface of the sole and to longitudinally draw the clamp into yielding contact therewith after the clamp engages the end of the shoe.

3. A sole pressing machine comprising a shoe supporting member, a coöperating sole pressing member, means for relatively oscillating the two members, a heel clamp, and means for operating the clamp to cause the latter to first advance into engagement with the heel end of a shoe and to there-

after move in a direction substantially normal to the surface of the sole into engagement therewith.

4. A sole pressing machine comprising a shoe supporting member, a coöperating sole pressing member, means for relatively oscillating the two members to level a shoe sole, a heel clamp, and means for moving the heel clamp toward the shoe constructed and arranged to cause an initial movement of the heel clamp in a direction substantially parallel to the surface of the sole until the clamp engages with the heel end of the shoe, and thereafter move the clamp in a direction substantially normal to the surface of the sole.

5. A sole pressing machine comprising a shoe supporting member, a lever fulcrumed upon the shoe supporting member, a heel clamp pivotally mounted upon the lever, means for oscillating the lever, and means for causing the heel clamp to rock about the outer end of the lever to move the heel clamp toward and from a shoe when the lever is oscillated.

6. A sole pressing machine comprising a shoe supporting member, means for oscillating the member, a heel clamp, a stationary cam, and connections between the cam and heel clamp for causing the latter to move toward and from the shoe when the supporting member is oscillated.

7. A sole pressing machine having, in combination, a shoe-supporting last, a co-operating sole-pressing form, a carrier, a last post adjustably mounted in said carrier, means to oscillate the carrier to level the sole of a shoe, a heel-clamp operating lever mounted on said post, a cam-lever, for controlling the operation of said clamp, mounted on said carrier, and contact connections between the cam-lever and the clamp-operating lever whereby the last post may be adjusted without effecting the operation of the heel-clamp.

8. A sole pressing machine comprising a carrier, means for oscillating the carrier, a post adjustably mounted in the carrier, a heel clamp supported upon the post, and mechanism supported upon the carrier for operating the heel clamp when the carrier is oscillated.

9. A sole pressing machine comprising a carrier, a post adjustably mounted in the carrier, a heel clamp supported upon the post, a stationary cam, and a bell crank pivotally supported upon the carrier to cause the operation of the heel clamp by the cam.

10. A sole pressing machine comprising a carrier, a post adjustably mounted in the carrier, a bell crank fulcrumed upon the post, a heel clamp supported upon one arm of the bell crank, a stationary cam, a second bell crank fulcrumed upon the carrier

and connecting the cam with the first mentioned bell crank to rock the latter when the carrier is oscillated, and means for rocking the heel clamp about the pivotal support when the bell crank is oscillated.

11. A sole pressing machine comprising a shoe supporting member, an arm fulcrumed at one end upon the shoe supporting member, a heel clamp pivotally connected to

the free end of the arm, a stationary arm, 10 a tail connected to the heel clamp and engaging beneath the stationary arm, a spring for retaining the tail in engagement with the stationary arm, and means for oscillating the pivoted arm to move the heel clamp 15 toward and from the shoe supporting member.
